UNITED STATES PATENT OFFICE.

MINNIE GRIFFITH, OF ALMIRA, WASHINGTON.

DRESSMAKER'S GAUGE AND CREAMER.

Application filed May 7, 1927. Serial No. 189,472.

My invention relates to a device for laying out and creasing cloth or other materials as used in dressmaking, and has for one object to provide a means for this purpose which shall be capable of being used without requiring the movement of the cloth intended to be laid out and creased.

Another object is to provide such a means in a readily portable form suitable for use by hand, simple to operate and easily manufactured.

With the above and other objects in view, my invention consists of the combination and arrangement of parts hereinafter described and claimed, it being understood that, within the scope of what is claimed, changes may be made in the precise embodiment shown without departing from the spirit of the invention.

20 In the drawings

Figure 1 is a plan view of my invention; Figure 2 is a section along the line 2—2 of Figure 1;

Figure 3 is a view of my invention in use 25 as a creaser;

Figure 4 is a view of my invention in use as a gauge.

Figure 5 is a section along the line 5—5 of Figure 1.

30 Figure 6 is a section along the line 6—6 of Figure 1.

Referring now more particularly to the drawings, A refers generally to a rectangular frame comprising a ruling edge 10 having the side bars 11 positioned thereon and extending right angularly rearwardly therefrom so as to be in parallel relation to each other; an upstanding creaser edge 12 is positioned on the said frame parallel and adjacent to said ruling edge 10 in parallel relation thereto; and a cross piece 13 ties the end of the bars 11 together so as to maintain the parallel relation of said bars. B refers generally to an adjustable member slidably positioned on said frame A in parallel relation

45 to the ruling edge 10, and comprising, in the preferred embodiment shown, a straight edge 14 positioned beneath the side bars 11 dependent from the upstanding cross member

50 15 adapted to have the said side bars 11 slidably passed therethrough as at 17 so as to permit the said cross member to project above the said side bars. A flat piece of metal or stiffening element 16 is fastened to 55 the backside of the said lip 15 by means of an upstanding flange 16^a provided on the said

element 16 and the terminal portions of the said element 16 are bent up and over and each end thereof is bent under and back upon itself so as to form a box like structure or 60 guide 18 slidably engaging the said side bars 11. The said straight edge 14 projects forwardly of the cross member 15 and element 16. Set screws 19 are provided in the said guide 18 to releasably lock the straight edge A in any desired parallel relation to the ruling edge 10. Appropriate divisions as at 65 21 are marked on the frame A to aid in the use of the device. The frame A is intended to be laid out in precise and parallel rectangular arrangement so that any edge of any of the members as ruling edge 10, side bars 11, cross piece 13, straight edge 14 and element 16, may be used for marking cloth if desired. 75

In the use of my invention as shown in Figure 3, a piece of cloth as at 22, being provided, the device is slidably positioned under the said cloth so that the edge 23 of the said cloth is positioned on the side bars 11 and the straight edge 14 and caused to bear against the said cross member 15, whereby the creaser edge 12 is caused to be in parallel relation to the said edge 23 of the cloth. Any suitable means may then be employed to impress a crease in the cloth corresponding to the creaser edge 12. 80

If it is then desired to lay out the cloth 22, the device is removed from the position as shown in Figure 3 and slidably positioned 85 over the said cloth so that the said edge 23 is positioned between the straight edge 14 and the side bars 11 and caused to bear against the said cross member 15 whereby the ruling edge 10 is caused to be in parallel relation to the said edge 23 of the cloth. Any suitable means may then be employed to impress a line on the cloth corresponding to the ruling edge 10. 95

It is obvious that the device may be employed as above described without moving the cloth, thereby simplifying the operation of laying out and creasing the said cloth. The device fills a long felt want, as it is accurate and a time saver. Banding, spacing 100 and creasing may be performed in an accurate manner, and many fancy figures, squares and lines may be made. I am aware that some gauges are made for marking widths, but they do not work as well as my 105 invention, inasmuch as the cloth has to be held flat and firmly so as to not ruffle up, 110

whereas in my invention the frame A acts in conjunction with the straight edge B to firmly hold the cloth while the marking is being done.

5 I claim:

1. A dressmaker's gauger and creaser, comprising a rectangular frame having a ruling edge fixed at one end thereof, an up-standing cross member adjustably and slidably mounted on said frame parallel relative to said ruling edge, a straight edge dependent from said cross member, said straight edge extending towards said ruling edge and also being spaced from and beneath said frame, and an upstanding creaser edge mounted on said frame parallel to and adjacent to said ruling edge.

2. A dressmaker's gauger and creaser, comprising a rectangular frame having a 20 ruling edge fixed at one end thereof, an up-standing cross member adjustably and slidably mounted on said frame parallel relative to said ruling edge, a straight edge dependent from said cross member, said straight 25 edge being spaced from and beneath said

frame and extending towards said ruling edge, a stiffening element mounted on said cross member, and box-like guides formed on the ends of said stiffening elements slidably engaging said frame.

3. A dressmaker's gauger and creaser, comprising a rectangular frame having a ruling edge fixed at one end thereof, an up-standing cross member adjustably and slidably mounted on said frame parallel relative to said ruling edge, a straight edge dependent from said cross member, said straight edge being spaced from and beneath said frame and extending towards said ruling edge, a stiffening element mounted on said cross member, each end of said stiffening element being formed into box-like guides having one of the parallel sides of said frame passed therethrough, means for locking said guides to said frame, and an upstanding creaser edge 45 mounted on the frame parallel to and adjacent to said ruling edge.

In testimony whereof I affix my signature.

MINNIE GRIFFITH.
